UNITED STATES PATENT OFFICE.

RICHARD COLBERT MASON, OF TULSA, OKLAHOMA.

WELL-MEASURING APPARATUS.

Application filed October 20, 1921. Serial No. 508,919.

To all whom it may concern:

Be it known that I, RICHARD COLBERT MASON, a citizen of the United States, and a resident of Tulsa, in the county of Tulsa 5 and State of Oklahoma, have invented certain new and useful Improvements in Well-Measuring Apparatus, of which the following is a specification.

The present invention relates to an improvement in well measuring apparatus of the type embodying driving wheels coacting with the cable or sand line to accurately measure the depth of the well.

The object of the invention is to provide an apparatus of this character in which the cable and driving wheels are positively constrained to corresponding motion, the cable being held at all times in driving engagement with the driving wheels and the driving wheels being governed to preclude their overrunning the cable.

Another important object is to provide an apparatus of this character which may be readily and conveniently arranged on the well casing in operative engagement with the cable and as readily disassociated therefrom when no longer needed.

Other objects and advantages of the invention reside in certain novel features of construction, combination and arrangement of parts which will be hereinafter more fully described and particularly pointed out in the appended claims, reference being had to the accompanying drawings forming part 35 of this specification, and in which:

Figure 1 is a perspective view, illustrating the preferred embodiment of the invention in operation;

Figure 2 is a view in side elevation parts 40 being removed and parts being shown in section for the sake of illustration; and

Figure 3 is a sectional view on line 3—3 of Figure 2.

Referring to the drawings wherein for the sake of illustration is shown the preferred embodiment of the invention, W designates the well casing into which the cable or sand line C is extended and upon which the well measuring apparatus constituting the present invention and indicated generally at M is mounted.

The well measuring apparatus comprises a main frame 10 preferably constructed of metal and including sides 11 and 12 having 55 reinforcing webs 13 and 14 respectively, and a bottom 15 and a top 16, both of relatively

heavy construction, as clearly shown in Figure 1. The side 11 consists of a straight piece of metal curved at its ends into the top and bottom, and the side 12 consists 60 of two half sections designated at 12^a and 12^b angularly arranged with respect to each other. The bottom 15 and top 16 are provided with U-shaped openings 17 and 18, respectively which are alined and accommodate the cable C in the operation of the apparatus.

A pair of bars 19 and 20 are provided, the bar 19 being arranged in seats 21 provided therefor on one side of the frame 10 70 and the bar 20 being arranged in seats 22 provided therefor on the opposite side of the frame, the bars 19 and 20 being parallel and opposite and extending longitudinally of the main frame. Bolts and nuts 23 extend through the bars and the frame to 75 secure the bars in position.

Driving wheels 25, 26 and 27 are arranged between the side bars 19 and 20 and are fixed on axles 28, 29 and 30 rotatably journaled in these bars. The driving wheels 25 and 27 are cut away to provide lightened wheel structures and comprise relatively thin central webs 25^a and 27^a and peripheral flanges 25^b and 27^b, respectively but the center wheel 26 comprises a solid stock of metal 85 and is relatively heavy to enable it to function as a governor.

Pinions 31, 32 and 33 are fixed on the axles 28, 29 and 30, respectively, and intermediate gears 34 and 35 coact with the pinions to constrain all of the driving wheels to corresponding motion, the intermediate gear 34 meshing with pinions 31 and 32 and the intermediate gear 35 meshing with 95 pinions 32 and 33. The intermediate gears 34 and 35 are journaled respectively on short shafts 36 and 37 carried by the side bars.

A tensioning device coacts with the driving wheels and includes a screw shaft 40 engaged in a threaded bearing 41 provided in the side 12 of the main frame. At its outer end the screw shaft 40 carries a hand wheel 43 and a tension block 44 is associated with the inner end of the screw shaft by 100 means of a swiveled connection 45. Adjacent the swiveled connection 45 the block 44 is hollowed out to provide a cavity 44^a, and in this cavity a compression coil spring 45^a is arranged and abuts the bottom of the 110 cavity at one end and a brass cup 45^b at its opposite end, the brass cup having a recess.

45° therein which engages the ball of the swiveled connection, as shown in Figures 2 and 3. At its ends the tension block is bifurcated to receive tension rollers 46 rotatably mounted on pintles 47 carried by the bifurcated portions of the tension block. The tensions are provided with peripheral grooves 47^a to receive the cable C.

A register 50 is provided and is carried 10 on a reversible bracket 51 consisting of an angular plate including a section 52 having spaced slots 53 and 54 adapted to receive either threaded studs 55 or threaded studs 56 accordingly as the well is being measured 15 so the cable is fed into or withdrawn from the well. In either event wing nuts 57 are threaded on the studs and engage the bracket to clamp it in position. The operating shaft of the register is connected to the axle of the 20 center driving wheel by a releasable coupling 58, as shown in Figure 1.

In operation the well measuring apparatus is positioned on the well casing, as shown in Figure 1, with the driving wheels and the 25 tensioning rollers engaging the cable or sand line. The length of the sand line and consequently the depth of the well is thus accurately measured since the driving wheels are firmly and positively engaged with the sand 30 line and moved at all times in absolute correspondence therewith. The tensioning device may be readily adjusted to meet the varying conditions and prevent the cable from slipping past the driving wheels and 35 the relatively heavy center driving wheel functions as a governor and prevents the driving wheels from overrunning the cable. The register takes its motion from the center driving wheel in either position of the 40 frame.

It is obvious that within the scope of the present invention the driving wheels as well as the rollers of the follower of the tensioning device may be constructed with or without flanges and present either a smooth surface or a grooved surface as desired.

I claim:

1. In a well measuring apparatus, a frame including a straight side, a side consisting 50 of angularly extending sections, and a top and a bottom having U-shaped slots adapted

to receive the sand line, a pair of bars carried by said top and bottom, axles rotatably journaled in said bars, driving wheels fixed to the axles and adapted to engage the sand 55 line, the center driving wheel being a solid stock and heavy to act as a governor, gearing constraining said driving wheels to corresponding motion, a second pair of bars carried by the top and bottom of said frame 60 and constituting guides, a tensioning device coacting with the driving wheels and including a threaded bearing formed between the angularly extending sections of said side, a screw shaft engaged in said threaded bearing, a hand wheel on one end of said shaft, a tension block operating between said guides, a swiveled connection between said shaft and said block and grooved tensioned rollers carried by said tension block, pairs 70 of threaded studs carried by the frame, a reversible bracket selectively cooperable with the pairs of studs, and a register carried by the pairs of brackets and driven from the center driving wheel in either position of the 75 bracket.

2. In a well measuring apparatus, a frame including a straight side, a side consisting of angularly extending sections and a top and a bottom having U-shaped slots, a pair 80 of bars carried by said top and bottom, axles rotatably journaled in said bars, driving wheels fixed to the axles, gearing constraining said driving wheels to corresponding motion, and a tensioning device coacting 85 with said driving wheels.

3. In a well measuring apparatus, a frame, driving wheels carried by the frame, the upper and lower driving wheels being cut away and lightened and the center driving wheel 90 being a solid stock and heavy to act as a governor and a tensioning device coacting with said driving wheels.

4. In a well measuring apparatus, a frame, driving wheels carried by the frame, a tension device coacting with the driving wheels, pairs of threaded studs carried by the frame, and a reversible bracket adapted to carry a register and selectively cooperable with either one of the pairs of studs.

RICHARD COLBERT MASON.
